UNITED STATES PATENT OFFICE.

FREDERICK BRUNO WAIBEL AND HENRY MEYTROTT, OF NEW YORK,
N. Y., ASSIGNORS TO THE MANHATTAN BRASS COMPANY, OF SAME
PLACE.

DESIGN FOR A CYCLE-LAMP.

SPECIFICATION forming part of Design No. 29,790, dated December 13, 1898.

Application filed October 27, 1898. Serial No. 694,750. Term of patent 3½ years.

To all whom it may concern:

Be it known that we, FREDERICK BRUNO WAIBEL, residing in the city and county of New York, and HENRY MEYTROTT, residing at Brooklyn, in the county of Kings, State of New York, citizens of the United States, have invented and produced a new and original Design for a Cycle-Lamp, of which the following is a specification.

- 10 In the drawings, Figure 1 is a side elevation of the lamp, and Fig. 2 is a plan view.

The general configuration of the lamp-body A is cylindrical, and the bottom portion B is enlarged approximately globular, as represented, and the front of the lamp C is conical, the smaller end of the cone being toward the cylindrical body A, and there are holes and ribs, substantially as illustrated in the draw-

ings, and a cap with holes above the conical front.

20 The leading feature of this design relates to the cylindrical body, the enlarged approximately globular bottom portion, the conical front portion, and the perforated cap above the cone.

25 What we claim as our invention, and desire to secure by Letters Patent, is—

The design for a cycle-lamp, substantially as set forth.

Signed by us this 22d day of October, 1898. 30

FREDERICK BRUNO WAIBEL.
HENRY MEYTROTT.
